UNITED STATES PATENT OFFICE.

CHARLES S. BOARDMAN, OF BUFFALO, NEW YORK, ASSIGNOR TO LACKAWANNA STEEL COMPANY, OF LACKAWANNA, NEW YORK, A CORPORATION OF NEW YORK.

PILE-FOLLOWER.

1,359,956.

Specification of Letters Patent. Patented Nov. 23, 1920.

Application filed April 15, 1919. Serial No. 290,233.

To all whom it may concern:

Be it known that I, CHARLES S. BOARDMAN, citizen of the United States, residing at Buffalo, in the county of Erie and State 5 of New York, have invented new and useful Improvements in Pile-Followers, of which the following is a specification.

This invention relates to the art of driving steel sheet piling and consists of an 10 improved sheet pile follower construction and arrangement designed particularly for use in subaqueous installations, and adapted for conveniently and easily driving sheet piling in interlocked relation below water 15 level without requiring the services of a diver. My present invention further consists in the essentially new and improved method employed in the interlocking and driving of the piling in installations of the 20 character described.

In the constantly expanding field in which interlocking steel sheet piling walls are found to be preferable and more economical, particularly as to installation costs there 25 are included constructions wherein it is necessary and desirable to drive the piling to form a wall having the top ends of the piling elements thereof driven below water level. In typical installations of this class 30 of construction, such as protective sheet piling walls driven at the base of dams and bulkheads these subaqueous protecting walls are installed as permanent parts of the structure particularly for protection against undermining.

In such installations it has heretofore been 35 customary and necessary in the driving of sheet piling to form a wall below the water level to employ a diver or divers, whose 40 services have been required to guide the individual piles or pile sections into interlocking engagement and to release the pile followers heretofore employed from their attachment to these individual piling sections. 45 In connection with these prior types of pile followers the follower elements have been attached by means of splice plates and bolts to the tops of piling sections, and after the piling section has been driven to the required depths as aforesaid the services of a 50 diver are required to detach the piling section from the follower element, the latter being then secured to the succeeding piling section which is guided into interlocking en-

gagement with the driven section by the 55 diver and then when driven the follower element would have to be again detached and so on until the completion of the wall. As will be readily appreciated this method of driving subaqueous walls is not only slow 60 and expensive in its operation but involves the further troublesome factor in that it depends upon the services of special apparatus and special labor.

In accordance with my present invention 65 I have designed an improved type of pile follower construction which in its use will permit of the piling sections being guided into proper interlocked relation from a point or position above water level and further 70 is adapted to release the piling after being driven to the depth desired below the water level by manipulation from a point thereabove so that the entire operation of guiding the sections into interlocking engagement 75 and releasing them from the follower elements is effected by manipulation at the surface thereby greatly facilitating the installation and correspondingly effecting a substantial saving in the expense thereof. To 80 this end I have devised a pile follower of improved form which is adapted to be releasably secured to the top of a pile or piling section and upon which the pile driver may act in driving each pile into submerged 85 position and which is further designed for engagement with a succeeding pile section and to guide the latter into interlocking relation with the first driven pile attached thereto.

In the use of my improved pile followers 90 I desirably employ two or more and of the same design, the same being used as aforesaid to guide the succeeding piling section into proper position and further similarly 95 guiding the follower of said latter pile section which is desirably effected by the interlocking and guiding engagement therewith. Accordingly this will permit of the following desirable method of operation being successfully carried out. The first piling section by means of a follower of my improved type attached thereto, is driven to the required depths, the second or succeeding piling section with a second follower attached 100 thereto will then be interlocked with the first follower element at top above water level and guided thereby through the inter-

locks of follower and steel sheet pile into proper interlocking engagement with first steel sheet pile driven as it is driven with its follower to the required depth. The first 5 follower will then be released by the means for that purpose hereinafter described and this follower will then be assembled with a third piling section which is then in turn driven as the succeeding section of the wall 10 through engagement with the second follower element still in position on the pile and which after the last named or third pile is fully driven is then released for use with a succeeding piling section or fourth steel 15 sheet pile. As will be readily understood this procedure of alternately releasing and withdrawing the first driven follower element after the succeeding element has been driven is continued until the length of wall 20 desired has been driven. When the latter is effected the two followers are then released leaving the completed wall driven at the desired depth below the water level, the entire manipulation of the sections and 25 followers having been effected at or above the surface. In driving the sheet piles by the foregoing improved method the proper alinement of the top of the wall driven is determined by the relative position of the 30 pile followers above water level.

The described and other features and advantages of my invention will be understood by reference to the accompanying drawing wherein an approved embodiment of my invention is illustrated and wherein like reference characters of this description are applied to the corresponding parts in the several views.

In the drawing Figure 1 is a side elevation illustrating the improved pile follower of my invention. Fig. 2 is a substantially central vertical sectional view thereof at right angles to Fig. 1 and on line 2—2 of Fig. 3. Fig. 3 is a horizontal sectional 45 view on line 3—3 of Fig. 2. Fig. 4 is a diagrammatic view illustrating the improved method of driving the pile sections in a continuous wall in accordance with my invention and Fig. 5 is a diagrammatic 50 view of a typical installation wherein the piling is driven as a permanent wall below water level.

In the embodiment of my invention as shown in the drawing herewith I have illustrated the same of a form particularly adapted for use with the well-known double interlock or "Lackawanna type" of steel sheet piling elements of the form illustrated in prior patent to me No. 923,110 dated May 60 25, 1909.

In constructing my improved follower element I desirably employ in the formation thereof a portion of a piling section of the type to be driven which is here shown at A. 65 This section A is of suitable length propor-

tional to the depth to which the piling is to be driven thereby and consists of a web portion 1 having integrally formed on its marginal side edges hook and guard flanges 2 and 3 forming an interlock adapted to 70 interlock with complementary and corresponding interlocks of an adjacent piling section. In my improved follower arrangement the interlocks as shown provide the guiding means which are instrumental in 75 the manner hereinafter described to guide the succeeding piling section into proper interlocking engagement with the first driven piling section below water level.

In forming the follower element the section A formed of sheet piling is reinforced by means of channel sections B, B secured by means of the rivets 6 to opposite sides of the web portion 1. Four of these channel sections B are employed having their web 85 portions in right angular relation to the web of the piling sections and secured to the pile section by means of their inner flanges 8. The channel sections B are as illustrated 90 symmetrically arranged with their opposed web portions suitably spaced to leave therebetween an opening 9 and as best shown in Figs. 1 and 2 the channel sections are extended or elongated below the bottom edge of the section A thereby forming oppositely 95 arranged and parallel slots or grooves 10 adapted to receive therein the web portion of the top of a piling section to be attached thereto and driven thereby. At suitable intervals longitudinally of the follower element so formed the channel sections B are secured together at their outer or side edges by means of plates 12 riveted to the flanges of said channel sections. At the lower end of the follower element the inner edges of 105 the web portion of the channel sections adjacent the slots 10 are cut away as shown in Fig. 2 so as to provide inclined surfaces 14—14 to guide the entry of the piling sections into the groove 10.

In assembling the pile followers so formed, with the steel piling section to be driven, the top portion of the piling section is received within the groove 10 with the top edge thereof in engagement or substantially in engagement with the follower piling section A as best shown in Fig. 1 where the piling section to be driven is indicated by dotted lines at P. When so positioned the piling section to be driven and the section A of the follower element are in vertical alinement with the bottom edge of the section A bearing upon the top surface of the piling section P so that the driving forces applied to the follower element by 110 the usual pile driver hammer will be transmitted directly through the section A to the piling P. As will be noted, the follower section A is reinforced against deflection under the blows of the hammer by means of 115 120 125 130

the described channel sections attached thereto and the channel sections further by means of their lower extending portions provide the means of supporting and holding the follower upon the piling section P and in proper alinement therewith.

Suitable means are provided for the purpose of securing the follower element and the piling section together until the latter has been driven and in accordance with my present invention I have designed an improved means which further is capable of being operated from a point remote therefrom, for instance by means of a chain or other connection which is extended to and operated from a point above the water level. The specific construction of securing means here employed and operable as aforesaid consists of a locking dog member 20 interposed between the channel sections shown at the left hand side of the follower and pivotally supported upon a pin or bolt 21 supported by said channels. This locking dog 20 is provided with an integral pin or lug 22 positioned to be received within the usual aperture provided in the top end portion of the piling sections P for pulling purposes. When so received within the piling aperture as indicated in Fig. 2 the follower and piling sections will be secured against separation. A retractile spring 25 is desirably arranged to have its ends connected respectively to an eyelet 25 formed integrally with the dog 20 and to a cross pin 26 supported in the channel members, the action of this spring being normally to move the locking dog in the direction of locking engagement with the piling section. Means for manually operating the locking dog for retracting said dog against the influence of the spring 24 is here shown consisting of an operating chain connection 27 connected at its lower end to an eyelet 28 integrally formed on the dog member 20 and upwardly extended to any desirable operating position above water level. This operating chain may desirably be attached at its upper end to the top of the follower. A protective or guard plate 30 is provided adjacent to the dog member to prevent injury thereto by contact with other parts during use. The dog 20 as here shown is so balanced upon the pin 21 that it will normally tend to rock into locking engagement when the follower is in vertical position so that it is not entirely dependent upon the spring 24.

From the improved construction of pile follower as described it will be seen that in the first instance there is incorporated in the follower element a section corresponding to the pile to be driven and in the arrangement whereby said section A bears directly upon and is in vertical alinement with the piling section to be driven; the registration 65 of the interlocks being assured by the en-

gagement of the lug 22 with the aperture in the pile section. It therefore follows that after driving of a section to its required depth the succeeding and adjacent piling section may be interlocked with said section 70

A of the follower element at the top portion thereof and above the water level and upon lowering the same it will be guided by this engagement into proper interlocking arrangement with the preceding driven pile. 75 It will further be noted that the pile follower of the latter section will also have similar engagement with the preceding or driven follower and accordingly may be driven to its full depth without interference from the former but on the contrary guided thereby. The first follower may then be released from the piling section driven there-through by withdrawing of the locking dog 20 by means of the operating 80 connection or chain 27 by a pull thereon sufficient to retract the dog against the influence of the spring 24. The follower may then be withdrawn and coupled up with the succeeding pile to be driven and the 85 cycle of operation repeated until the wall has been driven. Thus by my improved construction of follower elements and the resulting improved method of operation permitted thereby the driving of sheet piling 90 below water level may be accomplished by manipulation entirely at the surface whereby the work is not only greatly facilitated but the expense of such installation is materially reduced. This operation will be 95 more readily understood by reference to Fig. 4 wherein there is shown diagrammatically the method of driving piling in a continuous wall by means of two followers of my invention.

In Fig. 5 there is illustrated a permanent piling wall driven below water level in an installation of the general character for which my present invention is particularly adapted. Therein there is shown a bulk-head structure having its base protected by a wall of sheet steel piling P permanently positioned.

While I have described a desirable and approved embodiment of my invention it 115 will be understood that the same is capable of varied modification without departing from the scope of the invention and it is therefore intended that all matter contained herein shall be interpreted as illustrative 120 and not in a limiting sense.

I claim:

1. A pile follower adapted for driving sheet piling below water level comprising a follower member adapted to have bearing engagement with a pile section to be driven and securing means operative to attach the follower to the piling section by engagement with the latter and releasing means associated with the securing means 125 130

and adapted for releasing the latter from securing engagement, said releasing means being operative from above to permit of releasing the follower from the piling section 5 by manipulation at the surface substantially as described.

2. A pile follower adapted for driving sheet piling below water level comprising a follower member adapted for bearing engagement with a pile section to be driven, securing means carried by the follower member and normally operative to engage with the piling section to connect the follower and piling sections by engagement 10 with the latter and a releasing connection associated with the securing means and operative from above thereby to permit of releasing the follower from the piling section 15 by manipulation thereof at or above the surface substantially as described.

3. A pile follower adapted for driving sheet piling below water level comprising a follower member adapted for engagement with a pile section to be driven, securing 25 means operative to attach the follower to the piling section by engagement with the latter, means operative normally to move the securing means into position of engagement with the piling and a releasing connection 30 associated with the securing means and operative from above to permit of releasing the follower from securing engagement with the piling by manipulation at the surface substantially as described.

35 4. A pile follower adapted for driving sheet piling below water level comprising a follower member adapted for bearing engagement with a pile section to be driven, a securing element pivotally carried by the 40 follower member and adapted normally to engage with the piling section to attach the latter to the follower, and releasing means connected to the securing element and extended upwardly therefrom to permit of 45 releasing the follower from the piling section by manipulation at the surface substantially as described.

5. A pile follower adapted for driving sheet piling below water level comprising 50 a follower member adapted for bearing engagement with a pile section to be driven, a securing member pivotally supported upon the follower member and having a detent positioned to have securing engagement 55 with an aperture in the piling section, a resilient element connected respectively to the securing member and the follower member and operative normally to move the securing member into engagement with the 60 piling section and releasing means connected to the securing member and extending upwardly therefrom to permit of withdrawing the securing member from engaging position by manipulation at the surface substantially as described.

6. A pile follower adapted for driving steel sheet piling below water level comprising a follower member, said follower member being composed of a portion of a piling section of the type to be driven having reinforcing members attached thereto and extending therebelow for engagement with the piling section to be driven and to provide a guiding slot or groove to receive therein the top of said piling section and to guide the 70 latter into alinement and registration with the piling section of the follower, securing means carried by the follower member and operative to attach said member to the piling section to be driven by engagement with the latter and means for releasing said securing means from engagement with the piling section said latter means being connected to the securing means and adapted to be operated from a point above water 80 substantially as described.

7. A pile follower adapted for driving sheet piling below water level comprising a follower member, said follower member being composed of a portion of a piling 90 section of the type to be driven having reinforced members attached thereto and extending therebelow for engagement with the piling section to be driven and to provide a guiding slot or groove to receive therein 95 the top of said piling section and to guide the latter into alinement and registration with the piling section of the follower, a securing member pivotally supported on the follower member and operative normally to 100 engage with the piling section to be driven to connect same to the follower member and a releasing connection attached to the securing member and adapted to be operated by manipulation at a point above the water 105 level to effect the movement of the securing member to release the piling section substantially as described.

8. A pile follower adapted for driving steel sheet piling below water level comprising a follower member, said follower member being composed of a portion of a piling section of the type to be driven having reinforcing members attached thereto and extending therebelow for engagement with the 110 piling section to be driven and to provide a guiding slot or groove to receive therein the top of said piling section and to guide the latter into alinement and registration with the piling section of the follower, a securing member pivotally supported upon the follower member and provided with a detent disposed to have engagement with the piling 115 section to be driven to connect the latter to the follower, said securing member being shiftable at right angles to the piling section, a retractile spring connected respectively to the securing member and to the follower members and operative normally to move the former into securing position 120 125 130

and a flexible connection to the securing member adapted to be manipulated from above water level to withdraw said member from position of securing engagement substantially as described.

9. A pile follower adapted for driving steel sheet piling below water level comprising a follower member adapted to have driving engagement with a pile section to be driven, said follower member being composed of a portion of a piling section of the type to be driven having reinforcing channel members attached to each side of the web portion thereof, said channels being symmetrically arranged with their web portions in opposed relation and with a space therebetween and having their inwardly arranged flanges riveted to the web of the piling section and suitable spacing members connecting the outer ends of the channel members, said channel members being extended below the follower piling section for engagement with the piling section to be driven and to provide therebetween an entry slot for the latter piling section to guide the same into parallel alinement and registration with the follower pile section, a pivot pin supported by the flanges, at one side of the follower member, a securing member pivotally supported upon said pin and provided with a detent adapted to engage an aperture in the top portion of the piling to be driven, means normally acting to move the securing member into securing engagement with the piling section, said securing member being shiftable upon its pivotal support in a plane at right angles to the web of the piling section and provided with

a releasing connection attached to the rear of the securing member and extended to a position below water level to permit of manipulation thereof at the surface to withdraw the securing member from securing engagement with the piling section and a protective plate secured to the channel members in close proximity to the securing members substantially as described.

10. A pile follower adapted for driving sheet piling below water level comprising a follower member adapted for driving engagement with a pile section to be driven and provided with guiding means at the sides thereof adapted for guiding engagement with the interlocks of a piling section and with the corresponding means of a second follower member, the said guiding means of the follower member being adapted for registration with the interlocks of a piling section driven thereby, said follower element being provided with an entry slot for a piling section to be driven arranged to receive therein a piling section in parallel vertical alinement with the guiding means and with the interlocks thereof in registration with said guiding means, and securing means operative to attach the follower member to the piling section to be driven by engagement therewith and means for releasing the securing means from coupling engagement, said latter means being operative by manipulation from a point above water level substantially as described.

In testimony whereof I have signed my name to this specification.

CHARLES S. BOARDMAN.
